(57) **CLAIM**

The ornamental design for a direct radiating array antenna, as shown and described.

DESCRIPTION

FIG. 1 is a top perspective view of a direct radiating array antenna.

FIG. 2 is a bottom perspective view thereof.

FIG. 3 is a top view thereof.

FIG. 4 is a bottom view thereof.

FIG. 5 is a right side view thereof.

FIG. 6 is a left side view thereof.

FIG. 7 is a front view thereof; and,

FIG. 8 is a rear view thereof.

The broken lines illustrate portions of the article and form no part of the claimed design.
